UNITED STATES PATENT OFFICE.

EDWARD J. DE VILLE, OF DAYTON, OHIO, ASSIGNOR TO MONARCH ENGINEERING COMPANY, OF DAYTON, OHIO, A CORPORATION OF OHIO.

PUMP.

Application filed October 10, 1921. Serial No. 506,547.

To all whom it may concern:

Be it known that I, EDWARD J. DE VILLE, a citizen of the United States, residing at Dayton, in the county of Montgomery and State of Ohio, have invented certain new and useful Improvements in Pumps, of which the following is a specification, reference being had therein to the accompanying drawing.

10 This invention relates to pumps, and more particularly to domestic pumps of the deep well variety and the objects I seek to accomplish are:—

First, the provision of mechanism by 15 which I am enabled to use a high speed motor, such as an electric motor, with a low speed pump, whereby the high rotary speed of the motor is transformed into slow reciprocating motion and applied to the slow 20 moving piston rod of such a pump.

Second, the division of the power head into a base section to receive the water, a second section to form an enclosure for the operating mechanism and a third section 25 made removable to afford access to the bearings of the crank shaft, as also a support for the motor.

In the accompanying drawings forming a part of this specification:

30 Fig. 1 is a partial side elevation and sectional view of my improved pump.

Fig. 2 is a vertical sectional view of the same, showing the motor in elevation;

Fig. 3 is an enlarged vertical sectional 35 view of the upper portion of the casing showing the driving and driven sprockets, driving chain and oiling arrangement, taken on the line 4—4 of Fig. 1 and looking in the direction of the arrows;

40 Fig. 4 is a vertical sectional view of a part of the upper portion of the casing illustrating the driving worm and driven worm, crank shaft, worm gear and oiling arrangement, taken on the line 5—5 of Fig. 2 and looking in the direction of the arrows;

The numeral 1 designates an electric motor of any approved commercial type capable of developing high speed so as to rotate the driving sprocket 2, say 1750 revolutions per minute, or such a matter. This motor is mounted on the upper section 3 of my improved power head and this section in turn is fitted upon an intermediate section 4 to which it is connected, as by bolts or screws 5. Panels 6 in the nature of doors are made

removable so as to give ready access to the interior of this section at one side or the other; or the whole section may be lifted off by removing the screws or bolts 5, which will be the case in exchanging one size of crank and crank shaft for another and in exchanging one length of connecting rod section for another, as will hereinafter appear.

This intermediate section 4 consists of a shell-like structure having a removable plate 6 7 which leads into a compartment 8 enclosed by walls 9, made integral with the remainder of the section. This intermediate part also contains a compartment 10 enclosed by walls 11. A depending wall 12 65 from the upper section completes the enclosure of the compartment 10 which extends into the upper section. And it will be seen that an intermediate compartment 13 results from the presence of the walls 9, 11 and 12. 70

The lower portion of the section 4 has removable door-like plates 14 adapted to close an opening 15 and which when removed gives ready access to the operating parts within. The base section designated 16, to 80 which the section 4 is secured, as by bolts 17, comprises a hollow structure into which the water is delivered from the water cylinders. The channels within this base are designated 18 where the water enters and whence it passes through a valve 19 into the circular chamber 20 and from which it issues through either or both of the discharge openings 21 to which water pipes may be connected. A central opening 22 in the base section is 85 closed by a cap 23 to which the upper or plunger cylinder 24 is secured and which is held by screws 25, permitting of the removal of the cap for withdrawing the pump pistons and piston rods should occasion require, as hereinafter explained. The upper wall of this section 16 is fashioned with oil basins 90 26 into which the cross head dips to distribute a lubricant on its guides, as will be presently explained.

The upper wall of the section 16 is also provided with an opening 27 into which is fitted the air pump block 28; and an opening 29 over which is secured an air chamber 30 which communicates through the opening 29 with the chamber 20 in the base 16. 95

To this base is also attached the drop pipe 31, as by bolts 32. This pipe extends down into the casing of a bored well, or into any other type of well, such distance as the par- 100 110

ticular installation may require. The upper or so called plunger cylinder 24 depends into it, while the lower or lift cylinder 33 is located near the base of it, as by being connected with a valve seat spider 34 carrying a check valve 35 which lifts on the up-stroke and seats on the down-stroke. A conventional strainer 36 is usually attached to the foot of the drop pipe.

- 10 The piston-rod is usually made in two or more sections 37 and 38, coupled together in any well known way. The lower section 37 carries a conventional piston or so called lift bucket 39 with the usual check valve 15 40. And the upper section 38 carries a common kind of piston or plunger 41.

Thus the water pumps are constituted.

Referring now to the mechanism for operating the water pumps and the air pump, 20 after which I shall give a description of the air pump itself, it will be noted that guides in the form of rods 42 are mounted within the middle section of the head with their lower ends located in the lubricant basins 26 25 and their upper ends in the sockets 43. On these guides I mount a cross head 44, the lower tapered ends 45 of which are adapted to enter the lubricant basins 26 and pick up oil for lubricating the guides. The cross 30 head is secured to the upper section 38 of the water pump piston rod which passes through the bore 46 of the head and is supplied with nuts 47 above and below.

And to the cross head is also connected 35 the lower section 48 of the connecting rod which in any convenient way is detachably fastened to the upper section 49, as by an overlapped joint seen at 50, with the parts held together by bolts and nuts 51. The 40 lower section 48 is connected to the cross head by a wrist pin 52 kept in place by screw caps 53.

The upper section of the connecting rod is hung on a bearing 54 of the operating 45 crank 55. An oil chamber 56 and splash chain 57, within the connecting bar, cause lubricant placed in the chamber to lubricate the bearing 54. The stud shafts 58 of the crank are mounted in bearings, preferably 50 ball bearings, as seen at 59, supported by brackets 60 sustained in the intermediate section 4 of the power head. The crank shaft carries a disk 61 to which is attached a worm gear rim 62, as by screws 63. A worm pinion 64 mounted on a driven shaft 65 meshes 55 with the worm gear 62 and rotates it through motion received by the shaft 65 from the sprocket 66 generally located in the compartment 10, but extended down into a sump or 60 well 10^a. A driving chain 66^a is located within a housing 66^b built on to and above the upper section 3. This housing extends over and receives within it the motor driving sprocket 2. By these several means the driving 65 sprocket 2, the driven sprocket 66 and

the driving chain 66^a are all enclosed and kept dust free, as also lubricated in the manner now to be stated. Lubricant in the compartment 10 settles in the sump 10^a and is picked up by the travelling chain and carried to the sprocket 2, while the sprocket 66 travels in the body of lubricant. The rapid motion of the sprocket 66 and chain 66^a would soon exhaust the quantity of lubricant from the chamber 10 and sump 10^a unless the lubricant were returned as used. To this end there is formed within the housing 66^b an oil compartment 10^a which receives lubricant from the chain and housing above it. The lubricant runs back to the compartment 10 and sump 10^a through a spout 66^a. All this is clearly seen in Fig. 4.

Referring to Fig. 5 it will be seen that above the sump 10^a extends a partition 10^b with a small orifice 10^c to establish communication between the sump and the compartment 10. This partition prevents the sprocket 66 and chain 66^a from drawing the lubricant more rapidly from the compartment 10 than it returns thereto, by reason of the orifice 10^c permitting the lubricant from passing more rapidly into the sump 10^a than it returns to the compartment 10 through the spout 66^a.

The shaft 65 has suitable ball bearings in 95 the walls of this section, as shown at 65^a in Fig. 5.

The lubricant in the compartment is also taken up by the worm 64 and utilized in lubricating both the worm and worm gear. 100

It will be noted that the driving sprocket 2 of the motor is small compared with the diameter of the driven sprocket 66 and that in turn the worm pinion 64 is small compared with the worm gear 62. In the proportions shown, when the motor has a speed of 1750 revolutions per minute the worm 64 will revolve at 600 per minute and the crank 55 at but 45 revolutions per minute. Thus, a high speed small motor, economical in cost and current consumption may be used to operate my pump with its heavy water loads and strokes of pistons varying from four to six and eight inches with a crank 55 with a radius of two, three or four inches. These 110 figures are examples which conform to what my assignee, the manufacturer of this apparatus, is commercially practicing with this invention.

Referring again to the connecting rod and to the objects in forming it in detachable sections, it will be understood that two essential results are thus accomplished.

First, this permits of the use of cranks of different radius or throw without interfering with the sufficient descent of the cross head to take up the lubricant from the basins 26. When a short crank is used a longer section, say section 49, of the connecting rod is employed so that when the 120 125 130

crank is down the rod is still long enough to let the cross head enter the basins. When a longer crank is used a shorter section, say section 49, of the rod is employed. This 5 still permits the cross head to enter the lubricant basins.

Second, pumps whose pistons are of different lengths of stroke may be used with this power head by shortening or lengthening the connecting rod to agree with the length of the crank employed for the particular stroke of the particular pump.

Referring now to the air pump which is used to force air along with the water supplied by the water pump into the storage tank from which the water is to be forced by the expansion of the air through the distributing pipes, as in a house, it will be seen that this air pump consists of a cylinder 67 open at its upper end and fitted at its lower portion in the block 28. Within the block is a valve seat 68 against which closes an air valve 69 by means of a spring 70 located in a cage 71. When the valve 69 opens 25 downward air passes by it and through the cage into the chamber 20 and joins with the water in going to the pressure tank. The valve seat 68 is grooved at 72 so as to always communicate with a passage 73 and 30 through an orifice 74 with the interior of the air cylinder. As the passage 73 joins with a passage 75 which leads to a pet cock 76, the air forced by the pump may be diverted and discharged without passing into 35 the chamber 20, as will be the case when it is not desirable to pump any further supply of air into the storage tank. The pet cock 76 may be located within the section 4 of the head, as would be the case with the cock located as in Fig. 4, or it may be connected to the block 28 by an intermediate pipe 77, as seen in Fig. 1, and in this case be located out 40 of the power head.

The air pump piston rod 78 has at one 45 end a piston 79 which on the up-stroke collapses or recedes enough from the cylinder to allow of the accumulation of air under it, while on the down stroke it expands against the cylinder and forces the air out 50 of the cylinder. This rod is operated by a connection with the cross head through an arm 80 and nuts and lock nuts 81 above and below the arm. The arm is detachably connected to the cross head, as by a screw 82.

55 Thus the same cross head and power which operate the water pistons operate the air piston; and the same relation of speed as between the driving mechanism and the water pistons is maintained with reference to 60 the air piston.

The air chamber 30 is connected by a pipe 83 to the wall 9 of the section 4 of the head and opens into the compartment 8 and enables the air to act on the electric switch 65 generally designated at 84. The air acts

on the diaphragm 85 of this switch in the manner set forth in my copending application filed April 7th, 1921, Ser. No. 459,268. I will not, therefore, describe this matter in this specification. It is sufficient to say that when a predetermined degree of pressure is created in the storage tank the air under compression in the air chamber 30 will react and operate this switch or circuit breaker to cause it to open the circuit and stop the 70 operation of the electric motor. And likewise, when the pressure in the tank has been lowered sufficiently the switch or circuit breaker will automatically act through the spring 85^a and cause a closing of the circuit 80 to restore the motor and the pumping of air and water.

It is sometimes necessary to withdraw the water pistons and piston rods in these pumps, as for repairs. My construction 85 readily permits of this. Simply disconnect the cross head from the air pump piston rod, disconnect the sections of the connecting rod and disconnect and remove the section 4 of the power head from the base and remove 90 the cap 23, and then the water pistons and piston rods can be readily removed. The upper cylinder 24 will go with the cap 23.

It will now be seen that my invention comprehends an electrically operated pump possessing numerous features of marked advantage and practical utility.

Having thus fully described my invention, what I claim as new and desire to secure by Letters Patent, is:—

1. In a pump power head, the combination with a section having a lubricant containing compartment and a lubricant receiving compartment, of a high speed motor, power transmitting and speed reducing mechanism partly mounted within the lubricant containing chamber and partly mounted on the motor shaft and adapted to take up the lubricant from said compartment and lubricate the parts of said mechanism and to deliver the surplus to the lubricant-receiving compartment, the latter being adapted to discharge into the former chamber.

2. In a pump power head, the combination with a section having a lubricant containing compartment and a sump, and a lubricant receiving compartment, of a worm and its shaft and a meshing worm gear mounted in the lubricant containing 115 compartment, a sprocket wheel on said shaft operating in said sump, a high speed motor, a driving pinion on its shaft, a chain connecting said sprockets and adapted to lift the lubricant from the lubricant containing chamber to the driving sprocket and to deliver the surplus into said lubricant receiving compartment, this compartment discharging into the other.

3. In a pump power head, the combi- 130

nation with a section having a lubricant containing compartment, a sump, a dividing perforated partition, and a lubricant receiving compartment, of a crank shaft, a 5 worm gear, a worm pinion and its shaft, a driven sprocket on said shaft, a sprocket chain, a high speed motor, and a sprocket on its shaft on which said chain travels.

4. In a pump power head, a section having 10 an oil sump and a housing, of a driven sprocket mounted to revolve in said sump, a sprocket chain within said housing, a high speed motor, a sprocket on its shaft located within said housing and over which 15 said chain passes.

5. In a pump power head, a section having a lubricant containing compartment, a lubricant receiving compartment and a housing extended above said section, of a 20 high speed motor mounted adjacent said housing and having its shaft extended into it, a driving sprocket on said shaft, a driven sprocket in said lubricant containing compartment and a sprocket chain which connects 25 said sprockets and delivers the surplus lubricant into the receiving compartment, which latter discharges into the lubricant containing compartment.

6. In a pump power head, the combination 30 with a base section adapted to support the cylinders and drop pipe, an intermediate section, a cross head operable therein, guides for the cross head, and a connecting rod attached to the cross head, of 35 an upper section, a crank shaft mounted therein, to the crank of which said connecting rod is attached, a driven gear on said shaft and a driving pinion meshing therewith and also mounted within the 40 upper section.

7. In a pump power head, the combination with a base section adapted to support the pump cylinders and drop pipe, an

intermediate section, a cross head operable 45 therein, guides for the cross head, a connecting bar attached to said head, and an upper section, a crank shaft mounted therein to whose crank said connecting rod is attached, a worm gear on said shaft, and a worm pinion meshing therewith and mounted 50 in said section.

8. A pump power head having an upper portion divided off into a lubricant compartment and a crank compartment, a shaft bearing in each compartment, a shaft mounted in said bearings and having a crank in one compartment and a driven gear in the other, and a driving pinion mounted in the lubricant compartment and adapted to lubricate itself and said driven gear 60 with the lubricant contained therein.

9. A power pump head having an upper section divided into a lubricant compartment and a crank compartment, a shaft bearing mounted in each compartment, a shaft 65 carried by said bearings, a crank on said shaft in the crank compartment, a driven worm wheel on the shaft in the lubricant compartment, and a worm pinion mounted in the latter compartment. 70

10. In a pump power head, the combination with a base section having a central opening therethrough, a removable cap for said opening, a cylinder supported by said cap, an adjoining section of the head removable from the base, a cross head operable in the removable section and adapted to be detachably connected with the piston rod, whereby on disconnecting the cross head from the piston rod and on removing 75 the said section and said cap the piston rod and its attached devices may be removed from the well below. 80

In testimony whereof, I affix my signature.

EDWARD J. DE VILLE.
